Patented Sept. 15, 1914

Fig. 1

UNITED STATES PATENT OFFICE.

WILLIAM VREELAND BERGEN AND GROVER CLEVELAND COMBS, OF HILLSBORO,
OREGON.

ELECTRIC BELL-RINGER.

1,110,870.

Specification of Letters Patent. Patented Sept. 15, 1914.

Application filed April 5, 1913. Serial No. 759,108.

To all whom it may concern:

Be it known that we, WILLIAM V. BERGEN and GROVER C. COMBS, citizens of the United States, and residents of Hillsboro, in the county of Washington and State of Oregon, have invented a new and Improved Electric Bell-Ringer, of which the following is a full, clear, and exact description.

This invention relates to electric bell ringers of that type consisting of a reciprocating striking element or hammer located in proximity to the bell or gong to impinge upon the same, the device being especially useful in connection with fire or other alarm bells, church bells and other signal devices, where the bell sound is to be transmitted over great areas.

The invention has for one of its objects to improve and simplify the construction and operation of apparatus of this character so as to be reliable and efficient in use, comparatively inexpensive to manufacture and installed and designed so as to obtain a high speed of reciprocation of the striking element.

Another object of the invention is the provision of a simple and effective automatic switch for opening and closing the circuits of the solenoid or magnet, whereby the striking element or hammer will move back and forth with great rapidity and at the same time impart a blow of considerable power upon the bell.

Another object of the invention is to provide a solenoid and core which can operate in a magnetic field of high frequency without material heating of the parts.

With these objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention, and wherein similar reference characters are employed to designate corresponding parts throughout the several views, Figure 1 is a side view of the apparatus, showing the hammer or striking element at the end of its return stroke; Fig. 2 is a plan view thereof; Fig. 3 is a view of the striking element with portions thereof in section; and Fig. 4 is an enlarged view of the switch,

showing the same in open position and just prior to being closed by the return movement of the hammer.

Referring to the drawings, 1 designates the supporting base of the apparatus, on which is mounted the solenoid or magnet A, that is in the form of a spool through which passes the striking element or hammer B that is mounted to reciprocate preferably in a horizontal plane. The heads 2 of the magnet are preferably of copper or other non-magnetic material and have their bases 3 fastened to the support 1, and on the heads are mounted anti-friction or bearing rollers 4, that slidably support the reciprocating hammer B. The magnet or solenoid is composed of two windings or sections 5 and 6, either one or both of which may be connected in circuit, according to the magnetic power desired or the nature of the source of current supply. In order to prevent eddy currents from flowing around the heads 2, which are annular in form, each head has a radial slot or split 7. The hammer B is composed of a tubular body 8 filled with longitudinal strips or laminae 9 of iron or other magnetic material, and fastened to one end of the tube 8 is a striking head 10, and at the other end a weight 11 to give inertia to the element in moving on its striking stroke. The laminae 9 prevent eddy currents in the core formed by the reciprocating element B, and the outer tube 8 is split longitudinally, as shown at 12, Fig. 2, to prevent heating by eddy currents. The magnet or solenoid A is employed to move the hammer on its striking stroke, but springs 13 serve to return the hammer. These springs 13 are disposed at opposite sides of the magnet A and are of the helical extension type. The forward ends of the springs are connected with arms or equivalent devices 14 on the hammer head, and the rear ends of the springs are anchored at 15 on the rear head of the magnet. As the hammer is impelled by the magnetic force generated by the solenoid or magnet, the springs 13 expand and are placed under tension, and as soon as the magnetism drops the springs 13 come into play and retract the striking element B. In order to arrest the return movement of the striking element a stiff buffering spring 16 is arranged on a support or abutment 17 at the rear end of the base 1, and this buffering spring is dis-

posed in line with the weighted end of the hammer, so as to be engaged by such end near the limit of the return stroke.

The circuit of the electro-magnet can be closed in rapid succession where the striking is to be done automatically, or it may be closed by switches located at various stations from which the bell is to be controlled. For instance, when the bell is used for fire alarms the switches may be arranged in a fire engine house, police station, telephone exchange station, or other suitably designated place, and by opening and closing the circuit at predetermined intervals, according to some code, the bell can be sounded to give a signal indicative of the location of the fire. Where it is desired to ring the bell automatically in quick succession, a switch device as shown in Figs. 1 and 4 is preferably employed. This device comprises a movable contact 18 adapted to cooperate with one or more fixed contacts 19 and 20 which are connected with one of the circuit wires leading to the magnet A. This movable contact, which is adapted to bridge the contacts 19 and 20, is carried by the arm 21 of a lever l fulcrumed at 22 on the base 1, the said lever having an arm 23 which extends upwardly toward the hammer element B, so as to be in the path of a finger 24 projecting laterally from such element. Coöperating with the lever l is a latch 25 pivoted at 26^a on the base and extending upwardly into the path of the switch-actuating finger 24. This latch 25 has a shoulder 26 that is adapted to engage under the tip 27 of the contact-carrying arm 21 after the switch has been opened by the finger 24 striking the arm 23 of the lever l, and to bring about this action a spring 28 is connected with the arm 21 of the lever l, and with the latch 25 pulling the latter toward the said arm.

In operation, let it be assumed that the hammer element B is moving to the right, Fig. 4, under the power of the springs 13; the upper end of the latch 25 is just about to be struck by the finger 24, and as soon as the latch is struck the shoulder 26 of the latch is released from the tip 27 of the lever l, so that the spring 28 will pull the lever to the right and cause the contact 18 to bridge the contacts 19 and 20, the parts being now in the position shown in Fig. 1. The circuit of the magnet is accordingly closed by the switch and the magnetic attraction on the hammer element or core will cause the latter to immediately move to the left, allowing the latch to come into engagement with the end surface of the tip 27 of the lever arm 21, but the circuit will remain closed until the finger 24 strikes the lever arm 23, thereby raising the arm 21 to separate the contact 18 from the contacts 19 and 20. During this opening movement of

the switch a point is finally reached where the shoulder 26 can snap under the tip 27 of the contact-carrying arm 21. The circuit being thus broken the hammer element B immediately returns and again closes the circuit by the switch. By this arrangement a high speed of reciprocation of the hammer element can be obtained, and in actual practice an apparatus of approximately the proportions shown and three feet in length used in connection with an eight hundred pound bell produces a sound capable of carrying about two miles in foggy weather.

To prevent turning of the hammer element B the same is provided with a laterally-extending member 30 at its rear end, which moves back and forth in a slotted guide 31 mounted on the base 1 at the side of the hammer element opposite from the switch. By means of this guide 31 the finger 24 that controls the switch will be maintained in fixed relation to the lever l and latch 25.

From the foregoing description taken in connection with the accompanying drawings, the advantages of the method of operation and of the apparatus shown will be readily understood by those skilled in the art to which the invention appertains, and while we have described the apparatus which we now consider to be the best embodiment thereof, we desire to have it understood that the apparatus shown is merely illustrative, and that such changes may be made when desired as are within the scope of the appended claims.

Having thus described our invention, we claim as new and desire to secure by Letters Patent:

1. A bell ringer comprising an electro-magnet, a hammer element actuated thereby in one direction, means for moving the hammer element on its return stroke, a circuit for the electro-magnet, a switch for the said circuit including a movable member, means on the hammer element for engaging the movable member of the switch to open the circuit, and a latch for engaging the switch member to hold the same in open circuit position during the return stroke of the hammer element and released from the movable member of the switch by the said means on the hammer element to permit the circuit to close, said means being disposed and movable between the movable member and the latch.

2. A bell ringer comprising an electro-magnet, a hammer element actuated thereby in one direction, means for moving the hammer element on its return stroke, a circuit for the electro-magnet, a switch for the said circuit including a movable member, means on the hammer element for engaging the movable member of the switch to open the circuit, a latch for engaging the switch member to hold the same in open circuit

position during the return stroke of the hammer element and released from the movable member of the switch by the hammer element to permit the circuit to close, and a 5 spring connected with the latch and with the movable member of the switch to maintain the switch closed during the striking stroke of the hammer element, and to maintain the latch engaged with the movable 10 member of the switch during the major part of the return stroke of the hammer element.

3. A bell ringer comprising a reciprocating hammer element, electrical means for moving the same on the striking stroke, a switch including a contact-carrying lever, a latch arranged to hold the lever in open circuit position, a member on the element to engage the lever at the forward end of the striking 20 stroke, to open the circuit and to strike the latch at the rear end of the return stroke to release the latch from the lever, and a guiding device for preventing the hammer element from turning, whereby said member on the hammer element is maintained 25

in operative relation with the lever and latch.

4. A bell ringer comprising a magnet, a hammer element operated thereby, a switch controlling the circuit of the magnet and including a movable element, a device carried by the hammer element to impart a blow to the said movable element of the switch for quickly opening the same, and a latch disposed in the path of the device 30 to be released thereby and operatively connected with the movable element of the switch to engage with and hold such element in open circuit position during the major portion of the return stroke of the hammer 35 element.

In testimony whereof we have signed our names to this specification in the presence of two subscribing witnesses.
